UNITED STATES PATENT OFFICE.

ALBERT E. LONG, OF CHICAGO, ILLINOIS, ASSIGNOR TO STROMBERG ELECTRIC COMPANY, OF CHICAGO, ILLINOIS, A CORPORATION OF MAINE.

CORRECTIVE DEVICE FOR SECONDARY CLOCK MECHANISM.

Application filed August 29, 1925. Serial No. 53,282.

My invention relates to corrective device for secondary clock mechanism.

One of the objects of my invention is to provide an improved corrective device which can readily be applied to existing types of secondary clock systems.

A further object of my invention is to provide a corrective device which will be simple and reliable.

10 A further object of my invention is to provide a corrective device in which the corrective arrangement is controlled by the winding magnet of the master clock.

15 Further objects will appear from the description and claims.

In the drawings, in which my invention is shown,

20 Fig. 1 is a somewhat diagrammatic view showing the master clock in some detail and showing diagrammatically the relay, secondary mechanism and wiring arrangement;

Fig. 2 is a view of the master clock mechanism from the right of Fig. 1;

25 Fig. 3 is a view of the circuit controlling switch controlled by the winding magnet;

Fig. 4 is a section on the line 4—4 of Fig. 1; and

Fig. 5 is a section on the line 5—5 of Fig. 1.

30 The construction shown in the drawing comprises in a general way secondary electro-magnetic impulse mechanism such as a secondary clock 1 or a recorder 2 and a master clock mechanism for controlling the secondary mechanism having a time controlled

35 periodic low frequency switch 3 for normally controlling the impulses, and a time controlled periodic high frequency switch 4 for occasionally controlling the impulses (as for

40 instance if the secondary mechanism fails to respond) electromagnet impulse mechanism

5 for winding the master clock (controlled by the same impulses as said secondary mechanism) a switch 6 controlled by the

45 winding magnet for causing disconnection of the low frequency switch and connection

of the high frequency switch upon failure of the winding magnet and secondary mechanism to respond, whereby when the im-

50 pulses again become effective to cause re-

sponse of the secondary mechanism and winding magnet 7, the winding mechanism

55 will be advanced rapidly by the high frequency impulses, and means whereby the

high frequency switch will be automatically

disconnected and the low frequency switch again connected when the secondary impulse mechanism has been advanced into synchronism, thus restoring the normal low frequency control.

In the ordinary operation of the device the minute contact device 3 closes the circuit once per minute and this causes an impulse to be transmitted to the electro-magnet of the secondary mechanism 1 and 2 through the relay 8. However, if for any reason the winding magnet 7 (which is the same circuit as the secondary impulse mechanism) fails to respond, the selective switch 6 is operated to disconnect the minute contact device 3 from the relay circuit and connects the second contact device 4 in place thereof. The selective switch 6 stays in this position (in which the second contact device is in position to control the relay mechanism) so long as the secondary mechanism and winding magnet 7 fail to respond to the impulse. During this period the main spring 9 of the master clock is running down and is not periodically rewound as the winding magnet is inactive. However, as soon as normal conditions are restored so that the secondary mechanism and winding magnet 7 become responsive, the secondary magnets and winding magnet are used to operate rapidly under the high frequency impulses of the second contact device 4 and this rapid actuation continues until the secondary mechanisms and the winding magnet 7 have been brought back to normal, whereupon the selective switch 6 is caused to operate, to again connect the minute contact device 3 with the relay 8 and disconnect the second contact device 4.

The secondary mechanism, relay, winding magnet, selective switch, minute contact device, and second contact device will be described more in detail hereinafter. The mechanism by which the winding magnet 7 controls the selective switch will first be described in detail. The selective switch 6 is directly controlled by a pin 10 on a disk 11 which is secured to the hub 12 to which one end of the main spring 9 is secured. This pin 10 cooperates with the lower end of the switch lever 13 and when the pin 10 is in its normal position, holds the switch lever 13 in position to connect the minute contact device 3 with the relay. When, for any reason, the winding magnet fails to respond to the im-

pulses, the pin 10 moves downwardly away from engagement with this switch arm and permits the tension spring 14 to pull the switch arm 13 over, to disconnect the minute contact device 3 and connect the second contact device 4. When the winding magnet 7 again becomes responsive to the impulses, the pin 10 is quickly brought back to its normal position by the high-frequency impulses 10 and in this movement it engages the slanting cam edge 15 of the bottom of the switch lever 13 and operates the switch lever back so that the minute contact device 3 is again connected and the second contact device 4 is disconnected.

I will now describe the transmission from the main spring to the escapement of the master clock mechanism and the transmission from the winding magnet to the main spring. The transmission from the winding magnet to the main spring comprises an arm 16 which oscillates with the armature 17 of the magnet, a pair of links 18 pivoted to this arm at 19, a friction pawl 20 pivoted to these links at 21, a pair of similar arms 22 mounted to oscillate about the axis of the shaft 23, to which arms the friction pawl 20 is pivotally connected at 24, and a friction disk or ratchet wheel 25 engaged by the friction pawl 20 and secured to the hub 12 to which one end of the main spring is secured. The other end of the main spring is fixed to a pin 26 mounted on the frame-work. The construction has to be such that the friction pawl 20 will engage the edge of the friction disk 25 on a downward pull on the links 18 and such that the friction pawl will disengage and swing away from the friction disk 25 on the upward movement of the links. 40 In order to accomplish this, a stop pin 27 is provided to limit the upward movement of the oscillatory arms 22, so that as the spring 28 returns the arm 16 and the spring 29 lifts the oscillatory arms 22, the edges of these arms will engage the stop pin 27 before the end of the movement of the armature and links 18 so that further movement of the armature and links will throw the edge of the friction pawl 20 away from the edge of the friction disk 25 to permit clock-controlled movement of the friction disk, as hereinafter described.

The transmission from the main spring 9 to the escapement wheel 30 comprises the hub 12 previously referred to, to which the inner end of the main spring 9 is secured, a take-up or driving ratchet wheel 31 secured to this hub, a take-up pawl 32 engaging this ratchet wheel 31, a holding ratchet 33 on which this take-up pawl 32 is pivoted, a holding pawl 34 engaging the holding ratchet 33, a yielding transmission spring 35 wrapped around the hub 36 on which the holding ratchet 33 is mounted and having one end secured to the holding ratchet wheel,

a spur gear 37 to which the other end of this yielding transmission spring 35 is connected, mounted on a hub 38 secured to the shaft 23 on which one of the clock hands may be mounted, a pin 39 secured to the spur gear 37, and having one end lying in a slot 40 in the holding ratchet wheel 33, a pinion 41 meshing with the spur gear 37, a shaft 42 on which the pinion 41 is mounted, a spur gear 43 mounted on this shaft 42, and a pinion 44 meshing with this spur gear 43, this pinion 44 being mounted on the shaft 45 on which the escapement wheel 30 which cooperates with the verge 46 is mounted.

As will be pointed out more fully hereinafter, the periodic operation of the winding magnet 7 momentarily prevents the main spring 9 from being effective to cause pressure to be transmitted to the escapement wheel 30. It is in order to take care of this momentary interruption of the power of the main spring that the yielding spring and lost motion connection between the holding ratchet wheel 33 and the spur gear 37 are provided. During the greater period of operation, the spur gear 37 is driven directly from the holding ratchet wheel through the pin 39 engaging the rear edge of the slot 40 in the holding ratchet wheel 33. However, when for a moment the friction pawl 20 is acting to turn the friction disk 25, the tooth of the take-up ratchet wheel 31 which was engaged by the take-up pawl 32 is moved away from this pawl and the holding ratchet wheel is held against following after this take-up ratchet, by means of the holding pawl 34. While the holding ratchet wheel is thus held, pressure is exerted on the escapement wheel 30 through the yielding transmission spring 35, the pin and slot engagement 39 and 40 permitting the requisite relative motion of the spur gear 37 with respect to the holding ratchet wheel 33. When the winding magnet is deenergized, and the link again moved upwardly, another tooth of the take-up or driving ratchet 31 engages the take-up pawl 32 and the main spring 9 again becomes effective through the transmission described to cause pressure to be exerted on the escapement wheel 30.

In order to prevent over-winding of the main spring a pair of semi-cylindrical stop pins 47 and 48 are provided, one mounted on the clock frame and the other on the disk 11 secured to the main spring hub. These pins also limit the extent to which the main spring can run down in the event that the winding magnet becomes ineffective, this running down movement being limited to a single revolution of the disk, as at the end 125 of the revolution, the back-side of the movable pin 48 will engage the back-side of the fixed pin 47 and prevent further unwinding of the main spring.

In the ordinary operation of the master

clock, when controlled by the minute contact device, the winding magnet 7 is energized once per minute and from this it results that the friction disk 25 oscillates back and forth 5 one-sixtieth of a revolution in each direction. It moves slowly in a clockwise direction to move the semi-cylindrical pin 48 away from the fixed semi-cylindrical pin 47 during the escapement controlled movement 10 of the friction disk and it is moved quickly back to bring the movable stop pin 48 against the fixed stop pin 47 upon the energization of the electromagnet. This quick magnet controlled movement of the friction disk 25 also causes a corresponding retrograde movement of the take-up ratchet wheels 31 and brings a fresh tooth of this take-up ratchet wheel into engagement with the take-up pawl 32 mounted on the holding 15 ratchet wheel 33. The main spring is thus kept wound up by the periodic energization of the winding magnet. The oscillatory movement of the take-up or driving ratchet wheel 31 causes unidirectional rotation of 20 the holding ratchet wheel 33 and this unidirectional rotation is transmitted through the yielding transmission and gear train previously described, to the escapement wheel 30 which cooperates with the verge 46. 25 As previously pointed out, when the secondary mechanisms and winding magnet 7 are functioning normally, the switch controlling pin 10 is in engagement with the lower end of the switch arm 13, and the 30 minute contact device 3 is connected with the relay mechanism, but when the winding magnet fails to respond, the main spring 9 unwinds and is not rewound and the switch controlling pin 10 moves away from the 35 switch, permitting the spring 14 to throw the switch arm into position to disconnect the minute contact device 3 and connect the second contact device 4. While the details of the minute contact switch and second 40 contact switch are not claimed in this application, a brief description is necessary to an understanding of this invention. The minute contact switch comprises a pair of contacts 49 and 50 for controlling the relay circuit so arranged that when the control arms 51 and 52 are momentarily separated, once each minute by the action of the spiral cam 53, a circuit will be completed through the relay 8 which will cause a momentary 45 impulse to be transmitted to the secondary apparatus and to the winding magnet 7. To accomplish this the shorter controlling arm 51 has mounted thereon the contact 49 electrically connected with the binding 50 screw 54 which drops down onto the contact 55 50 on the longer controlling arm 52, which contact 50 is electrically connected with the other binding screw 55. When the shorter arm 51 drops off from the raised portion of 60 the cam 53 as shown in Fig. 1, the contact 65

49 carried thereby drops down and engages the contact 50 on the longer controlling arm 52. This completes the circuit between the binding screws 54 and 55 and hence closes the relay circuit. Upon slight further movement of the controlling cam, the longer arm 52 also drops off from the raised portion of the cam 53, and the contact 50 carried thereby drops away from the contact 49 carried by the shorter arm, and the relay circuit is 70 broken. 75

The second contact device comprises a spring finger 56 extending upwardly from the oscillatable verge shaft 57, two pairs of spring contact fingers 58, 58^a, 58^b and 58^c 80 controlled by said spring finger 56, and a pair of binding screws 59 and 60 connected to the wires 75 and 76, respectively, leading to the relay. The two outside spring contacts 58 and 58^c are connected by a conduct- 85 ing strap 63. In the construction shown, the circuit is completed when the spring finger 56 is moved to the left as shown in Fig. 1. The spring contact 58^a is connected with the binding screw 59 and the spring contact 58^c 90 is connected with the binding screw 60. The spring contact 58 is connected with the spring contact 58^c by means of the conductor strap 63. The circuit is from the screw 59, through the contacts 58^a and 58 and strap 95 63 to the bracket 64 into which the screw 60 is threaded. In the arrangement shown the circuit is completed only on the left hand swing of the swing finger, but if it should be desired to have a contact made on the 100 right hand swing also, this could be accomplished by providing another conductor strap similar to the conductor strap 63 electrically connecting the inside contacts 58^a and 58^b. This would of course double the 105 frequency of the contact device. The spring finger 56 oscillates with the verge shaft 57 and consequently closes the circuit once per second. There are thus provided two se- 110 lectively usable impulse controlling contact devices, one of which causes minute impulse, and the other of which causes second im- 115 pulses. The minute impulse contact device is the one which is in use normally, the second impulse contact device being brought into use only under abnormal conditions in which the secondary contact devices and winding magnet have failed to respond. As previously stated, the selective switch 6 controlled by the winding mechanism deter- 120 mines which one of the two contact devices is effective. The two contact devices 3 and 4 are connected in parallel between the terminals 65 and 66 of the relay 8. The terminals 54 and 59 of the two contact devices 125 3 and 4 are connected by the conductor 67 to the terminal 65 of the relay. The binding terminals 55 and 60 of the two contact de- 130 vices 3 and 4 are connected to the binding terminals 68 and 69, respectively, of the se-

lective switch 6 and the switch blade 70 of the selective switch is connected with the binding terminal 66 of the relay by means of a conductor 71. When the selective switch 5 is in a position shown in Fig. 1 the relay circuit is from the relay terminal 65 through the conductor 67, minute contact switch 3, conductor 72, selective switch contact 73, switch blade 70 and conductor 71 to the other relay 10 terminal 66. When the selective switch arm moves from a position shown in Fig. 1 to bring the switch blade 70 into engagement with the right hand switch contact 74, the relay circuit is from the relay wiring terminal 65 through the conductors 67 and 75, second contact device 4, conductor 76, selective switch contact 74, switch blade 70 and conductor 71 to the other relay 15 terminal 66.

20 The relay and secondary mechanism may be of any usual or suitable construction, and are not disclosed in detail. In the arrangement shown the relay magnet coils 77 and 78 are provided with an armature 79 which 25 operates a contact member 80 to move it into engagement with another contact member 81 to close the circuit for the secondary apparatus and winding magnet, which are connected in parallel with the wires 82 and 83 30 of the secondary circuit, by means of the wires 84. The circuit through the coils of the relay magnet is from the supply wire 85 through the coil 78, and contact circuit previously described to the wiring terminal 35 66 of the other relay magnet coil 78 and through this coil to the other supply wire 86. The circuit through the secondary apparatus is from the supply wire 85 through the conductor 87, switch contacts 80 and 81, 40 through the secondary line wire 83 and secondary apparatus, to the other secondary line wire 82 and back to the other current supply wire 86.

45 It will be seen that I have thus provided a master clock mechanism for controlling secondary apparatus having a simple and reliable corrective device for bringing the secondary apparatus back into synchronism if it has failed to respond to the impulses, and 50 more specifically that I have provided such a corrective device which comprises a normally operative low frequency periodic contact device and a high frequency periodic contact device which is substituted in the circuit for the low frequency device as soon 55 as the secondary apparatus fails to respond, and that the connection of the two controlling contact devices in the circuit is controlled by the winding magnet for the master clock which is in parallel with the secondary apparatus.

60 While I have shown but one form of my invention, it is to be understood that I do not desire to limit myself to this particular construction since many changes and modifica-

tions may be made therein without departure from the scope of the following claims.

I claim:

1. The combination with a secondary electromagnetic impulse mechanism of a master 70 clock for controlling said impulse mechanism having a periodic low frequency switch for normally controlling the impulses and a periodic high frequency switch for occasionally controlling the impulses, electromagnetic impulse mechanism for winding the master clock, controlled by the same impulses as said secondary mechanism, and means controlled by the winding magnet for causing disconnection of the low frequency 80 switch and connection of the high frequency switch upon failure of the winding magnet to respond to the low frequency impulses.

2. The combination with a secondary electromagnetic impulse mechanism of a master 85 clock for controlling said impulse mechanism having a periodic low frequency switch for normally controlling the impulses and a periodic high frequency switch for occasionally controlling the impulses, electromagnetic impulse mechanism for winding the master clock, controlled by the same impulses as said secondary mechanism, and means controlled by the winding magnet for causing disconnection of the low frequency 90 switch and connection of the high frequency switch upon failure of the winding magnet to respond to the low frequency impulses, said means comprising a member whose movement in one direction is controlled by 95 the escapement of the master clock and whose movement in another direction is controlled by the winding magnet.

3. The combination with a secondary electromagnetic impulse mechanism of a master 105 clock for controlling said impulse mechanism having a periodic low frequency switch for normally controlling the impulses and a periodic high frequency switch for occasionally controlling the impulses, electromagnetic impulse mechanism for winding the master clock, controlled by the same impulses as said secondary mechanism, and means controlled by the winding magnet for causing disconnection of the low frequency 110 switch and connection of the high frequency switch upon failure of the winding magnet to respond to the low frequency impulses, and whereby when the impulses again become effective to cause response of the secondary impulse mechanism, the winding mechanism will be advanced rapidly by the high frequency impulses, and whereby the high frequency switch will be automatically disconnected and the low frequency switch 115 again connected when the secondary impulse mechanism has been advanced into synchronism.

4. The combination with a secondary electromagnetic impulse mechanism of a master 120

clock for controlling said impulse mechanism having a periodic low frequency switch for normally controlling the impulses and a periodic high frequency switch for occasionally controlling the impulses, electromagnetic impulse mechanism for winding the master clock, controlled by the same impulses as said secondary mechanism and means controlled by the winding magnet for causing disconnection of the low frequency switch and connection of the high frequency switch upon failure of the winding magnet to respond to the low frequency impulses, and whereby when the impulses again become effective to cause response of the secondary impulse mechanism, the winding mechanism will be advanced rapidly by the high frequency impulses, and whereby the high frequency switch will be automatically disconnected and the low frequency switch again connected when the secondary impulse mechanism has been advanced into synchronism, said means comprising a member whose movement in one direction is controlled by the escapement of the master clock, and whose movement in another direction is controlled by the winding magnet.

5. The combination with a secondary electromagnetic impulse mechanism of a master clock for controlling said impulse mechanism having a periodic low frequency switch for normally controlling the impulses and

a periodic high frequency switch for occasionally controlling the impulses, electromagnetic impulse mechanism for winding the master clock, controlled by the same impulses as said secondary mechanism, and means controlled by the winding magnet for causing disconnection of the low frequency switch and connection of the high frequency switch upon failure of the winding magnet to respond to the low frequency impulses, said master clock having a coil torsion spring for driving it, having one end fixed and one end movable, said means comprising an oscillatable member whose movement in one direction is effected by the movable end of the coil spring and controlled by the escapement of the master clock and whose movement in the opposite direction is controlled by the winding magnet, and a rotatable member having a ratchet and pawl connection with said oscillatable member, whereby oscillation of said oscillatable member will cause step by step rotation of said rotatable member, and a yielding transmission between said rotatable member and the escapement, whereby pressure will be exerted on the escapement during the magnet controlled movement of the oscillatable member.

In witness whereof, I have hereunto subscribed my name.

ALBERT E. LONG.
